UNITED STATES PATENT OFFICE

2,461,063

GUARDRAIL FOR PERAMBULATORS

Samuel Karson, Cleveland, Ohio

Application February 12, 1947, Serial No. 728,181

4 Claims. (Cl. 296—36)

1

This invention relates to improvements in perambulators such as used for infants and the like, and more particularly to the provisions of means to prevent an infant from falling out of the perambulator.

It is an object of the invention to provide a device which can be quickly and conveniently attached to a perambulator to prevent an infant from falling out, and also to prevent other children from interfering with the child in the perambulator.

A further object is the provision of a device which can be attached to a perambulator to prevent a child from falling out, said device having means to prevent the child from tilting the perambulator.

These and other objects are attained by the novel construction and arrangement of parts hereinafter described and illustrated by the accompanying drawings, forming a part hereof, and in which:

Fig. 1 is a side elevational view of a device embodying the invention.

Fig. 2 is a plan view of the device.

Fig. 3 is an end view of the device.

Fig. 4 is a sectional view taken on the line 4—4 of Fig. 3.

Fig. 5 is a sectional view taken on the line 5—5 of Fig. 3.

Fig. 6 is a sectional view taken on the line 6—6 of Fig. 1.

Fig. 7 is a view of a clamp for attaching the device to a particular type of perambulator.

Fig. 8 is a view of a clamp for attaching the device to a different type of perambulator.

Referring to the drawings, the perambulator or crib attachment is shown to comprise front end posts 1 and rear end parts 2, which support a plurality of side bars 3, preferably made of wood or the like. Attached to each post 1 is a block 4 which supports end rods 5, which pass through an intermediate block 6. Attached to block 6 is a block 7 having a hole therein through which passes a staff 8, the latter being held clamped to the block by a bolt having a wing nut 9. The posts 1 and blocks 4 are preferably secured by screws, as likewise are the blocks 6 and 7.

Through the lower blocks 10 pass the lower rods 3, the blocks 10 having attached thereto vertical plates 11 which have flanges 20 having bolts with wing nuts to attach the device to the sides of a perambulator or crib.

It will be seen that the device can be quickly attached to a perambulator by affixing the clamps by means of the bolts and wing nuts 12.

15 The device has side bars and end bars prevent the child from falling out of the crib and also prevents other children from annoying the child in the crib. The attachment is a sliding device which can be slid the length of the crib for convenience. The members 11 are preferably of metal, and the block 7 is of hard wood.

A mortise is cut in the block 7 in which is positioned a ring 30 having an inside diameter 20 equal to the outside diameter of the staff 8. Block 7 is tapped and the winged bolt inserted. When the staff 8 is passed through the ring 30, adjustment can be made to any level by turning the winged bolt 9.

15 The length and width of the attachment can be made to accommodate the device to different sizes of cribs or perambulators.

In Figs. 7 and 8 are shown clamps which can be substituted to replace the clamp 11, 12 as shown in Fig. 3. In Fig. 7 the clamp comprises an S-shaped member with a block 15 to receive a rod 3, and has a vertical plate 14 with a loop 13 and a wing bolt 16 for attaching purposes.

In Fig. 8, an eye 16 receives the rod 3 and is connected to a bolt 17 and secured to the frame of a crib by a wing nut 18.

The above description is to be considered as illustrative and not limitative of the invention of which modifications can be made without departing from the spirit and scope of the invention as set forth in the appended claims.

The invention having been described, what is claimed is:

1. In an attachment for a perambulator, front 35 end posts and rear end posts on each side of the attachment, side bars supported by said posts, blocks attached to the rear posts, rear rods passing through said blocks, a vertical block at the rear through which the rear rods pass, a block 40 secured to the vertical block and having a hole, a staff passing through the hole, a wing bolt for holding the staff in the block, and means for clamping the lowermost side bars to a perambulator.

2. In a device adapted to be attached to a perambulator, pairs of front and rear end posts, a plurality of spaced side bars supported by said posts, blocks secured to the rear end posts, spaced rear rods supported by the blocks, a vertical 50 block through which the rear rods pass, a horizontal block attached to the vertical block and having a hole, a vertical staff passing through the hole, and means to clamp the staff to the horizontal block.

3. The structure set forth in claim 2 further

characterized by the horizontal block being mortised and having a ring therein through which the staff passes.

4. The structure set forth in claim 2 further characterized by the provision of blocks 5 through which the lowermost side bars pass, vertical plates attached to the blocks and having flanges, and wing bolts passing through the flanges to attach the device to the frame of a perambulator.

SAMUEL KARSON.
